AUTOMATIC FREQUENCY CONTROL
RECEIVERDudley E. Foster, South Orange, N. J., assignor
to Radio Corporation of America, a corpora-
tion of Delaware

Application January 5, 1938, Serial No. 183,419

8 Claims. (Cl. 250—20)

My present invention relates to automatic frequency control (AFC) arrangements for radio receivers; and more particularly the invention relates to an improved discriminator network 5 theretofor.

There has been disclosed in the past discriminator, or frequency response, networks for AFC arrangements, wherein the discriminator comprises a pair of separate diodes arranged in opposed relation with respect to an I.F.-tuned input circuit. The input circuit was constructed and arranged to impress on the diodes an alternating current voltage whose magnitude and phase depended upon the magnitude and sense of the I. F. energy 15 frequency shift. In such a discriminator network it has been thought necessary to employ independent cathodes for the two diodes. However, in the utilization of a discriminator network it is frequently desirable to ground the diode 20 cathodes. For example, a double diode tube of the type employing a common cathode could be employed. Again, a duo-diode-triode (or pentode) could be utilized thereby permitting the double diode section to be used for discrimination and 25 audio detection, while the amplifier section could be used for audio amplification.

Accordingly, it may be stated to be one of the main objects of my present invention to provide a frequency discriminator network employing a 30 pair of diodes having a common cathode, and the diode load resistors developing D. C. voltages whose relation is determined by the frequency deviation of signal energy impressed on the common input circuit of the network.

Another important object of this invention is to provide in a discriminator network of the 35 phase shift type, a pair of diode rectifiers provided with a common cathode; the rectifiers developing two D. C. voltages employed for frequency correction in a receiver, and the sum of 40 the voltages being used to provide a voltage for automatic volume control (AVC).

Still another desirable object of the invention is to provide in a discriminator network of the 45 phase shift type, a tube having a cathode common to a pair of diode sections and an amplifier section; the diode sections producing two D. C. voltages for AFC and AVC functions, and the amplifier section being used to amplify the audio output of the diode sections.

Still other objects of my invention are to improve generally the simplicity and efficiency of 50 automatic frequency control circuits for radio receivers, and more especially to provide AFC circuits which are reliable in operation and economical of construction.

The novel features which I believe to be characteristic of my invention are set forth in particularity in the appended claims; the invention 55 itself, however, as to both its organization and

method of operation will best be understood by reference to the following description taken in connection with the drawing in which I have indicated diagrammatically a circuit organization whereby my invention may be carried into effect. 5

In the drawing:

Fig. 1 shows a superheterodyne receiver embodying one form of the invention,

Fig. 2 graphically demonstrates the functioning 10 of the AFC discriminator.

Referring now to Fig. 1, there is shown a superheterodyne receiver circuit embodying an AFC circuit constructed according to my invention. The receiver generally comprises a signal collector 1; the latter may be grounded antenna, a loop collector, a radio frequency distribution line or the collector of a mobile structure such as an automobile. The signals collected by the collector 1 are impressed upon the tunable signal input circuit of the first transmission network. The latter may be a radio frequency amplifier followed by one or more tunable radio frequency amplifiers. For the sake of simplicity, the first network has been shown as the first detector 2; the tunable input circuit 3 thereof is coupled to collector 1. 15 The signals may be chosen from the broadcast band of 500 to 1500 kc.; if desired, the receiver can be of the multi-range type adapted to receive short wave signals as well. The local oscillator 4 may be of any desired type; it has a tunable 20 tank circuit comprising the variable tuning condenser 5 and coil 6. The oscillator is tunable over a frequency range which differs from the signal frequency range by the value of the operating I. F., the latter may be chosen from a range 25 of 75 to 450 kc. The rotors of the signal circuit variable condensers are arranged for mechanical uni-control with the oscillator condenser rotors; the dotted line 7 depicts such tuning mechanism. 30 The local oscillations produced by oscillator 4 are 35 impressed upon the first detector circuit; the I. F. energy is developed in the resonant circuit 8 40 which is tuned to the I. F.

The I. F. amplifier 9 is provided with an I. F.-tuned input circuit 10, the latter being coupled 45 to circuit 8. The I. F.-tuned output circuit 11 of the amplifier is magnetically coupled, as at M, to the circuit 12 which is resonated to the operating I. F. value. The high potential side of circuit 11 is coupled to the midpoint 14 of the coil 12 of 50 the secondary circuit 12 by the condenser 13 having a magnitude of approximately 50 mmf. The point 15 of circuit 12 is connected to the anode 17 of the tube 55 by condenser 18. The opposite point 16 of circuit 12 is connected to the 55 anode 19 of tube 55 by condenser 20. The condensers 18 and 20 may have a value of 50 to 500 mmf. The tube 55 is of the duo-diode triode type; the common cathode 21 is connected to ground through a bias resistor 22, the latter be- 60

ing shunted by an I. F. bypass condenser 23. The diode load resistors for both diodes are 24 and 25; the junction of the resistors is connected to cathode 21 and the resistor 22. The resistors may 5 each have a value of 500,000 ohms.

The midpoint 14 of the coil 12' is connected to ground through a resistor 26' of about 1 megohm in value; the plate 27 of tube 55 cooperates with cathode 21 and grid 26 to provide an audio amplifier section. The grid 26 is connected to resistor 26' so that grid 26 is at a proper negative bias for audio amplification; and, also, to derive an audio voltage therefrom. The plate 27 may be connected to a desired positive voltage source 10 by connecting it to such source through resistor 30. The amplified audio voltage is transmitted 15 through coupling condenser 31 to a following audio network.

The frequency control network comprises a 20 pair of electron discharge tube sections; in Fig. 1 these sections are shown disposed in a common tube envelope 32. The latter includes one triode having a cathode 33, a grid 34 and plate 35; and a second triode having a cathode 36, a grid 37 and a plate 38. The two cathodes are connected in common to ground through a biasing resistor-condenser network 39. Plate 35 is connected to one end of coil 40; the opposite end is connected to plate 38. The midpoint of coil 40 25 is connected to an energizing potential source for the plates 35 and 38. Coil 40 is magnetically coupled to tank coil 6.

There is connected in shunt across the tank circuit 5-6, a path including resistor 41 and condenser 42 in series. The radio frequency voltage developed across condenser 42 is applied in parallel to grids 34 and 37 through condensers 43 and 44. The tube 32 and its connections to the tank circuit 5-6 provide a "quadrature" type 30 frequency shift circuit. The plates of tube 32 are in push-pull relation to the oscillator tank circuit; the control grids are in parallel relation to the latter. Of course, the reverse relations may be used, as disclosed in my co-pending application Serial No. 130,630, filed March 13, 1937. The specific control tube arrangement shown in Fig. 1 is that disclosed in Fig. 2 of my said co-pending application.

The control grids of tube 32 are connected to 55 the discriminator diodes. Thus, grid 34 is connected by lead 45 to the anode end of resistor 24. Grid 37 is connected by lead 46 to the anode end of resistor 25. The direct current voltage developed across resistor 24 is filtered by series resistor 47 and shunt condenser 48. Resistor 49 acts as a coupling element between resistor 24 and grid 34. Resistor 50 and condenser 51 function as a filter network for the direct current voltage developed across resistor 25; resistor 52 60 acts as the coupling element to grid 37. The cathode 21 is connected to the junction of condensers 48 and 51.

The leads 45-46 have been designated as the "AFC" connections. It will be understood, particularly by reference to Fig. 2, that the AFC leads apply only negative voltage to grids 34 and 37. From a generic view, the action of tube 32 is to produce, or simulate, across tank circuit 5-6 positive and negative inductive reactances. 70 Although the grids 34 and 37 are at a common radio frequency potential, due to the push-pull coupling of plates 35-38 to the tank circuit 5-6 the inductive reactances simulated across the tank circuit will be of different sign. When the 75 grids 34 and 37 are at the same direct current

potential, and this occurs at a value f_0 equal to the operating I. F., then no frequency shift occurs in tank circuit 5-6. A change in frequency value of the I. F. energy results in an unbalance of the D. C. biases of the grids 34 and 37; since 5 these biases are different the A. C. plate currents of tube 32 will be unequal and a frequency shift in the tank circuit results. The direction of the frequency shift of the tank circuit depends upon the polarity of coils 6 and 40. Reversing the two 10 ends of coil 40 will reverse the direction of frequency shift.

Considering, now, the discriminator tube 55, it will be observed that the cathode 21 is connected to ground through the bias resistor 22. This 15 permits the use of a common cathode tube, instead of using a pair of independent diodes as in my aforesaid copending application. A distinct advantage in this type of circuit resides in the fact that a duo-diode-triode, or 55 type tube, 20 may be used, and the triode section is employed as an audio amplifier. Prior discriminator circuits of this "phase shift" type have not permitted the use of a common grounded cathode for the diode rectifiers; the present circuit read- 25 ily admits of the latter.

The functioning of the "phase shift" discriminator circuits 11-12 have been fully described by S. Seeley in application Serial No. 45,413, filed Oct. 17, 1935, Patent No. 2,121,103 issued June 21, 30 1938; it is not thought necessary to explain the circuit in detail. It is believed sufficient to point out that the "Diode" curves in Fig. 2 show the change in D. C. voltage produced across each diode load resistor as the I. F. energy departs in 35 frequency from the operating value f_0 . Each diode rectifier develops a D. C. voltage which is negative with respect to ground, but which is a maximum on one side or the other of the I. F. carrier value f_0 . The audio voltage (marked 40 "Audio" in Fig. 2) is tapped off from resistor 26'. In general, the audio voltage will, also, show two peaks on either side of the I. F. carrier value. Each of the filter networks 47-48 and 50-51 45 acts to remove the I. F. carrier component from the negative D. C. voltage applied over leads 45-46 to the control grids of tube 32.

In order to obtain AVC voltage which is symmetrical with respect to the frequency f_0 , resistors 66 and 70 are connected as shown to the 50 AVC lead. If these resistors are high in resistance compared to 24 and 25, the AVC voltage will be the average potential of that of the two diodes. This means that it will vary with frequency (I. F. value) in the manner illustrated in Fig. 2. Of 55 course, the AVC lead 80 will be connected to as many of the pre-detector tubes as may be desired. Suitable I. F. filters may be included in lead 80.

In actual operation, when the frequency of the 60 resultant I. F. energy differs from that to which circuits 11-12 are resonated, the D. C. voltage across one of the resistors 24, 25 is higher than that across the other. This produces an unbalance in the grids of tube 32, as regards negative potential; as a consequence of this unbalance there results a change in frequency in the direction to bring the I. F. energy back to normal frequency. The polarity of coil 12', relative to the 70 coil 11' determines which resistor, 24 or 25, will have to develop the greater D. C. voltage when the frequency of the I. F. energy is higher than the normal, or operating, I. F. value. Similarly, the polarity of coil 40 determines whether the 75

oscillation frequency will increase or decrease when grid 34 is more negative than grid 37.

While I have indicated and described a system for carrying my invention into effect, it will be apparent to one skilled in the art that my invention is by no means limited to the particular organization shown and described, but that many modifications may be made without departing from the scope of my invention, as set forth in the appended claims.

What I claim is:

1. In a detection network, a primary circuit, a secondary circuit coupled thereto, the two circuits each being tuned to a common frequency, means establishing the midpoint of the secondary circuit at the potential of one end of the primary circuit, a pair of diode rectifiers having cathodes at a common potential, a load resistor connected between each diode anode and cathode, and means for coupling the diode anodes to opposite ends of the secondary circuit.

2. In a detection network, a primary circuit, a secondary circuit coupled thereto, the two circuits each being tuned to a common frequency, means establishing the midpoint of the secondary circuit at the potential of one end of the primary circuit, a pair of diode rectifiers having cathodes at a common potential, a load resistor connected between each diode anode and cathode, means for coupling the diode anodes to opposite ends of the secondary circuit, and a direct current voltage connection to the anode side of each load resistor.

3. In a detection network, a primary circuit, a secondary circuit coupled thereto, the two circuits each being tuned to a common frequency, means establishing the midpoint of the secondary circuit at the potential of one end of the primary circuit, a pair of diode rectifiers having cathodes at a common potential, a load resistor connected between each diode anode and cathode, and means for coupling the diode anodes to opposite ends of the secondary circuit, said cathodes being a common cathode electrode, a common tube envelope housing the latter and the anodes of the rectifiers.

4. In a detection network, a primary circuit, a secondary circuit coupled thereto, the two circuits each being tuned to a common frequency, means establishing the midpoint of the secondary circuit at the potential of one end of the primary circuit, a pair of diode rectifiers having cathodes at a common potential, a load resistor connected between each diode anode and cathode, means for coupling the diode anodes to opposite ends of the secondary circuit, and means establishing said midpoint at said common potential.

5. In a receiver, an automatic frequency control system which includes a discriminator network, said network comprising a pair of diode rectifiers of the type including a single tube housing a common cathode and a pair of associated anodes, a signal input circuit connected to said anodes, a load resistance path connected between said anodes, means connecting the cathode to the midpoint of said resistance path, said midpoint being established at ground potential, and means for establishing the midpoint of said input circuit at ground potential.

6. In a superheterodyne receiver of the type including a frequency changer network, a local oscillator provided with a resonant tank circuit, an

intermediate frequency transmission network, a detection network which comprises a signal input circuit coupled to said intermediate frequency network, a tube provided with a pair of anodes and a cathode common thereto, means coupling the anodes to points of opposed alternating potential of said input circuit, a load resistor connected between each anode and said cathode, means establishing the junction of said resistors at ground potential, and means, responsive to the direct current potentials at the anode ends of said load resistor, for automatically regulating the frequency of said tank circuit.

7. In a superheterodyne receiver of the type including a local oscillator having a tank circuit and a first detector circuit having an intermediate frequency output circuit; the improvement which comprises an electron discharge tube having at least a cathode and two anodes to provide a pair of diodes, a resonant circuit coupled to said output circuit and tuned to the same frequency as the latter, means establishing the midpoint of the resonant circuit at the alternating potential of the high potential side of said output circuit, means connecting said cathode to said midpoint, means connecting said anodes to opposite sides of the said resonant circuit, a resistive path connected between said anodes and having the midpoint thereof connected to said cathode, a frequency control tube comprising a pair of electron discharge devices having a common output circuit coupled to said tank circuit, each device having an input electrode, means impressing an alternating potential derived from the tank circuit upon said input electrodes, and a direct current voltage connection between each of said input electrodes and its respective anode end of said resistive path.

8. In a superheterodyne receiver of the type including a local oscillator having a tank circuit and a first detector circuit having an intermediate frequency output circuit; the improvement which comprises an electron discharge tube having at least a cathode and two anodes to provide a pair of diodes, a resonant circuit coupled to said output circuit and tuned to the same frequency as the latter, means establishing the midpoint of the resonant circuit at the alternating potential of the high potential side of said output circuit, means connecting said cathode to said midpoint, means connecting said anodes to opposite sides of the said resonant circuit, a resistive path connected between said anodes and having the midpoint thereof connected to said cathode, a frequency control tube comprising a pair of electron discharge devices having a common output circuit coupled to said tank circuit, each device having an input electrode, means impressing an alternating potential derived from the tank circuit upon said input electrodes, and a direct current voltage connection between each of said input electrodes and its respective anode end of said resistive path.

9. In a superheterodyne receiver of the type including a local oscillator having a tank circuit and a first detector circuit having an intermediate frequency output circuit; the improvement which comprises an electron discharge tube having at least a cathode and two anodes to provide a pair of diodes, a resonant circuit coupled to said output circuit and tuned to the same frequency as the latter, means establishing the midpoint of the resonant circuit at the alternating potential of the high potential side of said output circuit, means connecting said cathode to said midpoint, means connecting said anodes to opposite sides of the said resonant circuit, a resistive path connected between said anodes and having the midpoint thereof connected to said cathode, a frequency control tube comprising a pair of electron discharge devices having a common output circuit coupled to said tank circuit, each device having an input electrode, means impressing an alternating potential derived from the tank circuit upon said input electrodes, and a direct current voltage connection between each of said input electrodes and its respective anode end of said resistive path, an audio utilization network coupled to said resistive path to derive therefrom the audio voltage developed thereacross, and an automatic volume control circuit connected to said resistive path to derive therefrom a direct current voltage whose amplitude is proportional to the amplitude of the intermediate frequency energy.
